UNITED STATES PATENT OFFICE

104,609

DESIGN FOR A SPACE HEATER

George L. Bridge, Ladue Village, Mo.

Application March 13, 1937, Serial No. 68,157

Term of patent 7 years

To all whom it may concern:

Be it known that I, George L. Bridge, a citizen of the United States, residing at Ladue Village, St. Louis County, Missouri, have invented a new, original, and ornamental Design for a Space Heater, of which the following is a specification, reference being made to the accompanying drawing, forming a part thereof.

The figure is a perspective view of a space heater, showing my new design, the undisclosed side being like the side shown.

The dominant feature of my invention resides in the provision of rounded corner column panels at the front of the space heater having transverse openings.

I claim:

The ornamental design for a space heater substantially as shown and described.

GEORGE L. BRIDGE.
